ANTITRANSMIT-RECEIVE SWITCH

Wallace C. Caldwell, Boston, Mass., assignor, by
mesne assignments, to the United States of
America as represented by the Secretary of War

Application July 9, 1945, Serial No. 604,016

1 Claim. (Cl. 333—13)

1
This invention relates to radio systems and more particularly to ultra high frequency systems involving wave guides.

In accordance with the present practice radar or radio locating equipment in operation at the ultra high frequencies may use a common radiating and receiving antenna. In such instances the transmitted signal must use a channel which, in part, is common to a part of the received signal channel. To prevent damage to the receiver from the transmitted signals, transmit-receive or T-R devices are inserted in the receiver channel near the point of juncture of the two channels. To prevent loss of the received signal in the transmitter, antitransmit-receive or ATR devices are inserted in the transmitter channel near the point of juncture of the two channels. One type of T-R and ATR device which is used with wave guides consists of a section of wave guide inserted in a series junction with the transmitter or receiver channel. As is well understood in the art, however, unless perfect contact is made between the T-R or ATR device and the wave guide, undesirable arcing will occur.

It has been found that if two ATR devices having the same resonant frequencies are used and placed approximately one-half wavelength apart a considerable increase in the band of frequencies over which the system will operate satisfactorily is achieved.

It is an object of the present invention, therefore, to provide an improved mount for a T-R or ATR tube in which arcing is minimized.

It is a further object of the present invention to provide an improved mount which permits two or more ATR tubes to be mounted within a minimum of space.

For a better understanding of the invention, together with other and further objects thereof, reference is had to the following description taken in connection with the accompanying drawing in which:

Fig. 1 is a sectional view of the invention showing two ATR tubes mounted; and

Fig. 2 is a sectional view on line 2—2 of Fig. 1.

Referring now more particularly to Fig. 1, there is shown in cross-section a mount 11 connected to a wave guide 12 and mounting ATR tubes 13 and 14. The tubes 13 and 14 are essentially a section of wave guide 15 terminated at one end by a mounting flange 16 and at the other end by an iris 21, the opening of which is sealed with a substance 22 such as glass. The tubes 13 and 14 are filled with an inert gas and sealed off by the plugs 23. The wave guide section 15 is effectively

terminated by a plate 24 in which one or more openings such as opening 25 allow the gas to circulate freely. Screws 26 or other means are used to secure the tubes 13 and 14 to the mount 11. 5 The distance from the inside of the wave guide wall to the edge of the flange 16 is denoted by D.

In Fig. 2 there is shown a detailed view of one mount taken along the line 2—2 of Fig. 1. The section 31 is the narrow wall of the wave guide 12 and the section 32 is a portion of the mount 11. A recess 33 cut in the wall 31 allows the tube 13 or 14 to be inserted to sufficient depth in the mount 11 so that the iris 21 and seal 22 are flush with the broad wall of the wave guide 12. A recess 34 in the mount 11 prevents contact between the tube 13 or 14 and the mount 11.

In the operation of this device including an ATR tube it is desired to have a minimum of reflection of energy back toward the source from the device during high level transmission and to have a maximum of reflection of energy back toward the source from the device during low level reception. The high level transmitted signal indicated by arrow 36 will cause the tubes 13 and 14 to arc over across the opening of the iris 21. The impedance of this arc is very small, and since this arc is effectively in series with the wave guide 12 the effect is as desired. In series with the arc there exists an apparent open circuit between the walls of the mount 11 and tube 13 or 14. If the distance D is made equal to an integral number of half wavelengths, the short circuit which exists between the wall of the mount 11 and the flange 16 will be transformed into a short circuit at the wall of the wave guide 12. It has been found that if D is equal to one-half wavelength, undesired characteristics are obtained as a function of frequency; however, these undesirable characteristics are not present if D is equal to one wavelength, and this length is, therefore, recommended. From the foregoing it is apparent that there has been obtained a minimum impedance in series with the wave guide, and the energy 36 will be transferred with a minimum of reflection. The action of the mount is the same for received signals, the only difference being that the tube does not arc over, and it, therefore, presents a high series impedance which causes a maximum of reflection. From Figs. 1 and 2 it will be seen that the ends of the tubes 13 and 14 are flush with the inner surface of the wave guide wall and therefore no physical discontinuities exist to cause undesirable reflections.

This mount may be used to cover another range 55 of frequencies than that for which originally de-

signed if the length D of the choke is altered. This may be achieved without altering the mount 11 by milling a recess in the flange of the tubes as indicated on tube 14 at 35 in Fig. 1. However, note that the two tubes are identical in any given instance and the milled recess is made in both or neither accordingly.

The terms "transmit-receive switch" and "antitransmit-receive switch," commonly referred to as TR and ATR switches, are used in the specification and claim with the following conventional means. A TR switch is an electronic switch which prevents the transmitted pulses from excessively overloading the radar receiver, but allows the received energy, which is much weaker, to reach the receiver without appreciable loss. It is placed in the wave guide or transmission line adjacent the receiver and between the receiver and the antenna, which is used for both transmission and reception. The ATR switch is an electronic switch placed in the wave guide or line adjacent the transmitter and between the transmitter and the antenna, and serves to effectively disconnect the transmitter from the antenna during reception to prevent loss of the received signal in the transmitter.

While there has been described what is at present considered the preferred embodiment of the invention, it will be obvious to those skilled in the art that various changes and modifications 30 may be made therein without departing from the invention.

What is claimed is:

In a radar system comprising a pulse transmitter and an antenna interconnected with a 35

10

5

tubular wave guide having an opening in one wall thereof, an antitransmit-receive switch having a gas filled rectangular resonant cavity with an electrical gap included in said opening, a metallic rectangular enclosure consisting of side mounting flanges and an end plate, said switch being mounted inside said enclosure on said end plate and extending to the opening in said wall of the wave guide with the switch spaced from the wall of the wave guide and entirely external to the wave guide, said metallic enclosure and said resonant cavity being closely juxtaposed for a distance substantially equal to one wave length at the operating frequency of the wave guide so as to form a wave guide choke across the space between said switch and the wall of the wave guide, said switch being positioned in the wall of said wave guide whereby high level transmission produces ionization of the gas in said resonant cavity and consequent closure of the gap which effectively closes said opening in the wall of the wave guide.
